WELL SURVEY SYSTEM

Emmett M. Irwin, Pasadena, George E. Lewis, Alhambra, Richard H. Duval and Bruce H. Rule, Pasadena, and Ray M. Chenoweth, West Los Angeles, Calif., assignors to Cooperative Development Co., Los Angeles, Calif., a corporation of California

Application October 4, 1938, Serial No. 233,208

12 Claims. (Cl. 255—1)

Our invention relates to systems for making surveys or other measurements in oil wells and has particular reference to systems for converting measurements taken at great distances below the ground surface into signals which may be transmitted to the ground surface and there translated substantially simultaneously with the making of the measurement.

In the oil well industry it is frequently necessary to obtain information relative to the various conditions existing in the well at great distances below the ground surface. One such condition is that of determining whether or not a well bore in the process of drilling is following the true vertical line and, if not following such line, at what angle the bore is deviating therefrom from the true vertical. Another such condition is that during the drilling of the well, it is frequently necessary to not only determine the angle of deviation of well bores from the true vertical, but also to determine the compass direction in which such bore is deviated. It is also frequently desired to survey the course which has been taken by a well bore, either at some point during the drilling thereof or after the drilling has been completed.

The instruments which are at present employed for obtaining such information may be roughly classified in two classes:

(1) Those in which the determinations made by the instrument are recorded within the instrument itself requiring the instrument to be removed to the ground surface before the desired information is received; and

(2) Those in which the information is transmitted to the ground surface over an electrical signalling circuit extended from the ground surface through the well bore and to the instrument.

Both of these classes of instruments embody numerous disadvantages and it has been long recognized that great savings in time and money could be effected were it possible to overcome these disadvantages.

In a copending application, Serial No. 162,792, filed September 7, 1937, by Emmett M. Irwin, Ray M. Chenoweth and Richard H. Duval, there is disclosed a means for overcoming these disadvantages by transmitting signals to the ground surface as sound signals which are conveyed by the metal drill string used to rotate the drill bit.

The present invention is directed to a similar device and is directed particularly to a signal transmitting system which employs the column of mud or drilling fluid contained within the interior of the drill string as a transmission medi-

um, thus avoiding the high transmission losses encountered when an attempt is made to transmit signals through the metal of the drill string.

It is, therefore, an object of our invention to provide a sound transmission system by which a relatively weak signal produced within the well may be readily transmitted to the ground surface with a sufficiently small loss in amplitude to permit reception and recording of the same at the ground surface.

Another object of our invention is to provide a system for transmitting signals produced in an instrument located in a well to the column of fluid existing in the well and for receiving such signal direct from the column of fluid at the ground surface, whereby the efficiency of the liquid column as a sound transmission medium may be readily employed.

Another object of our invention is to provide an instrument for making measurements at any desired location within an oil well and which may be exposed to the mud stream or other liquid circulating in the well without substantial injury to the instrument.

Another object of our invention is to provide an instrument of the character set forth in the preceding paragraph wherein the instrument may be permanently located upon a drill string or other string of tubing extending into the well directly in the mud stream circulating through the well without interference with the free circulation of mud or other drilling fluid in the well and with little or no injury to the instrument by reason of abrasive action of the mud fluid on the instrument.

Another object of our invention is to provide an instrument of the character set forth in the preceding paragraph with a mounting device by which the instrument may be located directly in the drill string without interference with the ready passage through the drill string of solid objects such as core barrels or other devices normally passable through a drill string unequipped with our instrument.

Another object of our invention is to provide an inclination measuring device in which a plurality of instrumentalities are employed and adapted to measure a different condition or different angle of deviation of the instrument from the vertical with an improved relay device by which each of the individual measuring instrumentalities may be brought into play in a predetermined sequence in a time cycle.

Another object of our invention is to provide a measuring device which may be lowered into or

disposed in an oil well, the instrument being self-contained and in which means controllable from the ground surface are provided for selectively rendering the instrument active or inactive.

Another object of our invention is to provide an instrument of the character set forth in the preceding paragraphs with a control means which will set the instrument in operative condition and with means for disconnecting motive power from the instrument at the expiration of a predetermined time after the instrument has been rendered operative.

Another object of our invention is to provide an instrument of the character set forth in the preceding paragraphs with a control switch of extremely rugged construction adapted to control the electric circuits and which will not be subject to destruction under the abuse which would be encountered in the normal handling of the instrument in the well.

Other objects of our invention will be apparent from a study of the following specification read in connection with the accompanying drawings wherein:

Fig. 1 is a diagrammatic view of an oil well borne in the course of a drilling operation and illustrating our invention as embodied in a device for measuring the angle of deviation of the well bore from the vertical.

Fig. 2 is a cut-away view of one form of instrument for measuring the angle of inclination of the well bore from the vertical and embodying the features of our invention.

Fig. 3 is a detailed vertical sectional view of one form of mounting device which may be interposed in a drill string or tubing string to mount and locate our instrument at a predetermined point in the well bore.

Fig. 4 is a horizontal sectional view of the mounting device shown in Figure 3, the section being taken along line IV—IV of Figure 3.

Fig. 5 is an enlarged vertical sectional view of the signal producing and transmitting device constituting a part of the instrument shown in Figure 2.

Fig. 6 is an enlarged view of the goose neck connection or mud hose connection which may be employed at the ground surface and showing the manner in which the signal pick-up device embodying the principles of our invention may be attached thereto.

Fig. 7 is an enlarged vertical sectional view of a signal receiver or pick-up device shown in Figure 6.

Fig. 8 is a diagrammatic view of one form of electric wiring arrangement which may be employed to interconnect angle measuring devices and signal producing devices constructed in accordance with our invention.

Fig. 9 is a detailed vertical sectional view taken through one form of vibration responsive switch which may be employed in the practice of our invention.

Fig. 10 is a horizontal sectional view of the vibration responsive switch shown in Figure 9, the section being taken along line X—X of Figure 9.

Fig. 11 is a vertical sectional view taken through one form of controlling relay which may be employed in the practice of our invention.

Fig. 12 is an exploded perspective view of the contact carrier and contacts constituting a part of the relay shown in Figure 11.

Referring to the drawings, we have illustrated a typical well drilling installation in Figure 1,

in which a well bore 1 is illustrated as being in the process of drilling by means of a drill bit 2, coupled through an instrument mounting device 43 to a drill collar 3, which is in turn connected 5 at the lower end of a drill string 4 made up in the usual manner of a plurality of sections or lengths of drill pipe extending upwardly to the ground surface 5, where the drill string is coupled by means of a kelly 6 to a rotary table 7 driven or rotated by means of any suitable power apparatus 8. Drill string 4 is supported upon a swivel 9 which is in turn suspended from a traveling block 10 of a block and tackle assembly of which the stationary or crown block 11 is supported upon the upper end of a derrick structure or tower 12.

As is the usual practice of oil well drilling, the swivel 9 constitutes a means by which mud fluid or drilling fluid may be circulated down through 20 the drill string 4 and upwardly about the drill string 4, to carry away the cuttings, the mud fluid being pumped into the drill string 4 by means of any suitable well known pumping apparatus supplying this fluid through a mud hose 13 extending to pumps not shown.

The well bore 1 in Figure 1 is illustrated as being disposed in the true vertical direction throughout the major portion of its length but the lower end of the well bore is illustrated as 30 having deviated from the vertical at the point 14 so that, should the drilling operations be continued under the conditions illustrated in Figure 1, the well bore will not have its longitudinal axis extending along the true vertical but will instead extend at a considerable angle to the vertical.

The primary difficulty heretofore encountered in maintaining the well bore along a true vertical line or axis has been that the information 40 to the effect that the well bore has deviated from the vertical is not available to the driller or operator of the well until after such deviation has continued for a considerable depth of crooked hole, it being frequently necessary to plug back 45 the crooked portion of the hole and re bore the same in order to insure the return of the bore to the true vertical alignment. This difficulty may be avoided by providing an instrument which may be permanently secured to the drill string and located reasonably close to the drilling bit and actuated, in response to the cessation of actual 50 drilling operation or to a short pause in the rotation of the drill bit, to notify the driller whether or not the bit is then making a true vertical bore 55 or has deviated from the vertical.

Such an instrument may be constructed along the lines illustrated in Figure 2 and may include a suitable case or housing 15 within which is located a plurality of angle measuring devices 60 or units 16 each comprising a disc-like base member 17 (see also Fig. 8) having an upper surface 18 upon which a ball or other rolling member 19 is adapted to be supported, the surface 18 having a depression 20 therein into which 65 the ball 19 normally rests when the housing member 15 is disposed with its longitudinal axis in the true vertical, but adapted to allow the ball to be displaced from its normal or central position when the housing 15 is tilted away from the true vertical position by an amount exceeding 70 the angularity of the surface 18.

The surface 18 is preferably conical so that the ball will normally rest at the apex of the cone, that is, centrally of the surface 18, so that when 75 the housing is tilted as above stated the ball will

roll from the center and toward the outer edge of the base 17 until it engages a contact ring 21 disposed slightly above the base member 17 and insulated therefrom.

The construction of each of the angle measuring units 16 may be identical except for the angle or the pitch of the cone-like surface upon the base so that the ball employed in the unit will move from its normal position to its contacting ring position when the housing 15 is tilted at a different angle from that at which the balls of the remaining units will respond. It will be understood that as many of such units 16 may be employed as desired and the pitch of the cones of each of these devices may be varied in such manner as to cause each of the balls to measure a different angle in progressively increasing small increments. There is a sounding device or signal producing device indicated generally in Figure 2 by reference character 22, this device being illustrated in detail in Figure 5. As will be more fully explained hereinafter, the signalling device is adapted to be consecutively connected in circuits with each of the angle measuring units 16 so as to be actuated by or in response to any of these units which have been so tilted as to move their associated balls to contact making position. As a means for consecutively connecting the angle measuring units 16 to the sounding device 22, we prefer to provide a plurality of relays 23 arranged in an electric circuit herein-after more fully described. Each of the relays 23 is preferably constructed as illustrated in Figures 11 and 12 as small relay members or units having an external diameter adapting them to be readily received within the housing 15 and to be stacked one upon the other in a relatively small vertical space.

In addition to the relays 23 we provide switching apparatus which will automatically place our instrument in operative condition when the actual drilling operations are stopped or paused but which will normally hold the instrument in a non-operative condition during the actual rotation or drilling operations of the bit. We have illustrated one of such switching devices as a vibration responsive switch 24 arranged as illustrated particularly in Figures 9 and 10 to complete the circuit through its contacts whenever vibrations or motion of the switch ceases but which will whenever shaken or vibrated move its contacts away from circuit closing position. If desired, a second vibration responsive switch 24A may be provided which will disconnect circuits established by the switch 24 at some predetermined time after these circuits have been established.

The housing 15 may also include a suitable source of electric current for operating the relays 23 and the sounding or signalling device 22, such source of current being illustrated in Figure 2 as comprising a plurality of small unit dry battery cells 25.

The instrumentalities contained within the housing 15 are so arranged that whenever the drill bit or drill string to which the instrument is attached comes to rest a sufficiently long period of time to permit the vibration responsive switch 24 to close its contacts, power will be supplied from the source of current or batteries 25 by 60 which a signal impulse or vibration producing device, such as is indicated at 22, will be actuated a number of times within a given time cycle or period depending upon the number of angle measuring devices 16 which have been so tilted

away from the true vertical that their respective balls have been moved into contact with the contact ring 21.

There is preferably at least one operation of 5 the sounding device during each time cycle to act as a monitor telling whether or not the instrument is in operative condition, independently of whether or not any of the angle measuring devices have been moved away from their normal 10 positions. Whenever the signal producing device 22 is actuated a pressure wave or series of sound or signal vibrations will be generated by the signalling device to be received at the ground surface and there translated or recorded in terms 15 of angle of deviation measurement.

The particular signalling device 22 illustrated herein is especially adapted to produce signals or sound vibrations of a predetermined frequency to be transmitted directly to the mud stream 20 or other column of liquid which may be contained within the well, so as to utilize the known high efficiency of transmission of sound or vibration signals through a body of water or other similar liquids.

25 As shown in Figure 5, the sounding device 22 is preferably mounted at the upper end of the housing 15 and includes a diaphragm 26 constructed as a suitable disc of metal, the diameter of which is preferably as large as can be securely 30 supported within the open end 27 of the housing 15.

35 The diaphragm disc 26 is preferably held in the end of the housing 15 by means of a cap ring 28 threaded as indicated at 29 upon the upper end of the housing 15 so as to press the diaphragm 26 into tight engagement with a mounting ring 30 screwed into the interior of the upper end of housing 15, a suitable gasket 31 being interposed between the lower surface of 40 the disc 26 and the mounting ring 30 to prevent the ingress of water, mud or other fluid into the interior of the housing.

45 Suspended from the mounting ring 30 is an interior cage or frame 32 in which is mounted a solenoid coil 33 within which operates a core 34 adapted to be drawn upwardly upon energization of the coil 33. The core 34 is made of any suitable magnetic material and is provided upon its extreme upper end with a striker head 35 of non-magnetic material adapted to engage a weight 36 suspended from the center of the diaphragm disc 26 by means of a resilient rod 37. By properly selecting the length and diameter of the resilient rod 37 and the mass of the weight 36, a blow by the solenoid core 34 upon the weight 36 will cause the diaphragm disc 26 to be vibrated at a predetermined frequency.

50 It is desirable that the weight of the core 34 be balanced by means of a spring 38, so that the initial pull by the coil 33 need be only sufficient to accelerate the core during its upward stroke thereof, the spring 38 being mounted below the coil 33 by means of a mounting disc 39 secured to and extending across the inner cage 32. The spring 38 has one of its ends secured to a rod 40 which in turn is rigidly secured to the core 34 while the opposite end of spring 38 is secured to an adjusting sleeve 41 threaded as indicated at 42 into and through the mounting disc 39. By 55 suitably adjusting the sleeve 41 up and down toward the coil 33, length of stroke of the core 34 may be selected. The coil 33 is adjustable vertically in the mounting cage as by means of screws 33a in elongated slots 33b to so position 60 the coil that the "dead center" position of the

core is with the hammer 35 just free of the weight 36. Thus the hammer 35 will strike only a single blow upon the weight 36 for each energization of coil 33. Also the mass of the core 34 should be but slightly less than the mass of the weight 36 so that its rebound after impact will be sharply defined but of such low energy that it will be readily brought to rest by the effect of the energized coil.

It follows, therefore, that if the housing 15 is located upon the drill bit, drill collar or other portion of the drill string in such manner as to expose the diaphragm 26 to the mud fluid, circulation fluid or other liquid column in the well, the signal vibrations resulting from an impact upon the weight 36 will be transmitted directly to the liquid column and thence upwardly to the ground surface.

While the housing 15 may be mounted in any suitable manner to expose the diaphragm 26 to the mud stream or liquid column, we prefer to employ a special mounting device illustrated particularly in Figs. 3 and 4 for the purpose of permitting direct contact between the diaphragm 26 and the liquid column without in any manner obstructing the circulation of mud or other drilling fluid through the drill string and also to avoid undue wear or abrasion upon the instrument by reason of the passage of the drilling fluid past the instrument. The mounting device preferably includes the special sub 43 which may be mounted directly above the regular drill collar employed to mount the drill bit upon the string, such special sub being constructed of extra heavy large size drill pipe having an interior opening 44 somewhat in excess of the mud fluid or circulation opening in the regular drill pipe employed in the string.

The upper end of the sub 43 is provided with a coupling member 45, either constructed integrally with the sub 43 or as a part separate therefrom to provide a connection or coupling by which our special sub may be connected to the regular tool joints employed in the particular drill string with which it is to be associated. Similarly, the lower end of the sub 43 is provided with a coupling member 46 by which the special sub may be coupled with regular tool joints to the drill collar employed in the string.

Mounted within the enlarged opening 44 in our sub is an instrument carrier 47 which is preferably shaped as indicated in Fig. 4, having a cross section including at one side of the sub 43 an instrument tube 48 having an internal bore of a suitable size to receive the housing 15 containing the instrumentalities hereinbefore referred to. Extending from the instrument tube 48 are a pair of wings or webs 49 formed of a thin walled V-shaped section of metal the outer legs of the V shape joining each other at 50 and terminating in a counterweight 51.

By referring particularly to Fig. 3 it will be observed that the instrument carrier 47 including the instrument tube 48, the wings 49 and the counterweight 51, provides an elongated mounting for the instrument housing 15 at one side of the special sub while the sub will be balanced by the counterweight 51 in such manner as to permit relatively rapid rotation of the drill string without undue vibration.

While the special sub 43 may be of any desired length, we prefer to construct the same of a length somewhat in excess of that which is required to accommodate the length of the instru-

ment housing 15, so that a spacing collar 52 may be employed above the instrument carrier 47 to provide an entirely unobstructed relatively large diameter passage for mud or other circulating fluids. Thus, mud fluids coming down through the regular drill string, will enter the sub 43 through a relatively restricted passage 53 in the tool joints and coupling member, at which time the mud fluid is travelling at a relatively high velocity. However, as the mud fluid enters the enlarged passage defined by the spacing sleeve 52 the velocity of the fluid will be materially reduced and any abrasive action upon the upper end of the instrument carrier 47 and particularly upon the upper end of the housing 15 which is exposed directly to the mud stream will be materially reduced.

The diaphragm will vibrate against an upwardly directed column of liquid so that the greater portion of the energy in the diaphragm will be directed upwardly toward the ground surface.

By reason of the construction of the instrument carrier 47 a relatively large area of unobstructed passage is provided through the sub 43 for the mud fluid, as well as for other tools such as core barrel or other devices commonly lowered through the drill string. The counterweight 51 may either be made solid or, if desired, 25 may be provided with a longitudinally extending bore 51a to act as a housing for a portion or all of the battery cells 25 employed in our instrument and thus the length of the housing 15, the sub 43 and carrier 47 may be materially reduced. 30 The use of the counterweight 51 for this purpose also permits the employment of a large number of battery cells without requiring elongation of or increase in length of the housing 15 or the sub used to mount it.

40 Also if desired the apices of the V shaped wings 49 may also be formed as tubular housing members for additional dry cell batteries if desired.

All of the instrumentalities contained within the housing 15 as well as the various dry cell batteries employed, either in the instrument housing or mounted separately in the instrument carrier 47, are separated from the cooling effects of the mud stream or circulating fluid by only 45 relatively thin metal walls so that effective cooling of the instrument and batteries is accomplished by the continuous circulation of the circulating fluid.

The signals of such predetermined frequency as the signalling device may be selected to produce, 55 as hereinbefore described be transmitted upwardly through the fluid column in the well to the ground surface where the same may be received and translated by suitable receiving apparatus which includes a sound or pressure wave responsive mechanism exposed to the effect of the pressure waves sent up through the liquid column as by extending such mechanism into direct contact with the liquid column or sufficiently close thereto that the transmission qualities of the liquid column may be effectively utilized. This mechanism may be inserted into the bore to contact the liquid column or as shown in Fig. 6 such signal receiving device may be mounted in a housing 55 which may be attached to or formed as an integral part of the usual 60 goose neck 56 by which mud fluid is pumped into the drill string at the ground surface (see Fig. 6).

As shown in Fig. 7, the housing 55 is provided 70 at one of its ends with a cap 57, the central

portion of which comprises a relatively heavy diaphragm 59 capable of responding to vibrations or sound signals imparted to it by the liquid column impinging upon the cap 51. A suitable microphone 58 is illustrated as being mounted within the housing 55 to receive and respond to vibrations of the diaphragm 59. While the microphone 58 may be of any desired character, we prefer to use a crystal type of microphone since it is peculiarly adapted to be secured to and form a part of a weight 58a which is in turn coupled to the diaphragm 59 by means of a resilient rod 60. By selecting the length and diameter of the rod 60 and the mass of the weight 58a (plus the mass of the microphone 58) the diaphragm 59 and the microphone 58 may be tuned to the same frequency to which the signal sending device 22 was tuned and thus the microphone 58 will respond only to vibrations of the selected or predetermined frequency and will not readily respond to other vibrations or sounds emanating from the well or from other apparatus employed in connection with the well such as mud pumps, hoisting equipment, etc.

For the purpose of assisting in the assembly and adjustment of the microphone 58, weight 58a and rod 60, we prefer to mount the same upon a cylindrical inner frame 61 as by extending a perforated diaphragm or spider 62 across the interior of the frame 61, securing the outer edge of the diaphragm between clamping rings 63 and 64 secured in any suitable manner to the frame 61 and to secure the rod 60 through the center of the perforated diaphragm 62 as by means of adjustable lock nuts 65. Likewise, the weight 59 is mounted upon the upper end of the rod 60 by means of threading the end of the rod into a threaded bore 66 in the weight 58a and locking the same at any desired adjusted position by means of a lock nut 67. By providing suitable hand openings 68 in the frame 61 access may be had to the interior of the frame 61 to reach the lock nuts 65 and 67 for adjustment purposes.

The microphone 58 is illustrated as being coupled through a suitable amplifier 70 to a recorder 71 or to an audible translation device such as earphones 72, the circuit preferably passing through a band-pass filter indicated at 73 to assist further in limiting response of the recorder 71 and earphones 72 only to the selected predetermined frequency emitted by the signal sending device 22.

The signalling device 22 and angle measuring devices 16 may be connected in a circuit such as that illustrated in Fig. 8 which is especially adapted to a relay construction of such a character as will permit its use under the tremendous vibrations, strains and abuse to which the instrument may be subjected during the drilling operation. Such relay structure is illustrated herein in Figs. 11 and 12 as comprising a body member 74 which includes a disc-like portion 75 from the center of which extends a cylindrical stem 76 constituting the magnetic core of the relay. A coil 77 is mounted upon or wound upon the stem 76 and suitably insulated therefrom as by means of a tubular section 78 of insulating material frictionally secured to the stem 76 and having a disc 79 of insulating material interposed between the upper end of the coil 77 and the inner surface of the disc portion of the housing 74. A second disc 80 of insulating material may be applied at the lower end of the insulating tube 78. The stem 76 preferably extends slightly beyond the lower end of insulating tube 78 and has

surrounding its extreme lower end a spacer member or disc 81 preferably made of copper as will be more fully described hereinafter for the purpose of imparting time delay response of the relay to energization of the coil 77.

5 A protective shell 82 constructed of magnetic material surrounds the coil 77, the upper end of the shell 82 abutting the body member 74 and being preferably received in a recessed portion 10 83 thereof. Shell 82 may be constructed of a length considerably in excess of the length of the core or stem 76 so that the lower end of the shell 82 may be employed as a housing and for mounting a plurality of contact members to be actuated by the coil.

15 The movable contact piece or armature of the relay is illustrated as comprising a metal ball 84 suspended in an elongated cylindrical bore 85 to move toward and away from the lower end of the stem 76 as the coil is energized and de-energized 20 respectively. The bore 85 is defined by aligned central or axial openings in discs 86, 87 and 88 of insulating material which are also employed as the means for insulating and mounting the contact pieces to be engaged by the movable ball or armature member of the relay.

25 The relay is provided with a plurality of "normally open" contacts 89a, 89b and 89c, each of these contacts being constructed as sector shaped 30 portion of thin suitable metal, the contacts 89a and 89b being identical in construction, and each of them provided with a tail piece or connection terminal 90 by which electrical conductors may be connected to the respective contact members. 35 The contact member 89c is likewise provided with a terminal lug or extension 91 by which electrical connection may be made thereto.

30 The intermediate insulation disc 87 is provided upon its upper face with a series of sector shaped 40 depressions 92 extending therein to a depth substantially equal to the thickness of the material from which the contact members 89a, 89b and 89c are formed, so that the contact members when seated in the depression will have their 45 upper surfaces flush with the upper face of the disc 87.

45 Referring now to Fig. 11, the contact members 89a, 89b and 89c assembled upon the disc 87 and inserted into the shell 82 will be rigidly held in 50 place by abutment with the thin upper insulation disc 87.

55 The apices of the contact members 89a, 89b and 89c project inwardly to some extent within the cylindrical bore 85 within which the contact ball moves so that whenever the coil 77 is energized the ball 84 will be drawn upwardly toward the stem 76 and will engage the extending apices of the contact members 89a, 89b and 89c, thereby 60 completing the electric circuit between all three 65 of these contact members. By reason of the use of three of such contact members it will be apparent that the ball will make three point contact with these contact members and will positively engage and bridge between contact members 89c and 89a and contact members 89a—89b and contact members 89c and 89b, thus insuring complete electrical connection between all of the contacts.

70 The underside of the disc 87 is similarly provided with sector shaped depressions which are adapted to receive and hold therein a duplicate set of contact members 89d, 89e and 89f, the apices of which project inwardly of the bore 85 to such extent that whenever the relay coil 77 is de-75 energized the ball 84 will drop upon and inter-en-

gage all three of the contact members, thus providing "normally closed" contact members to be utilized in the circuit hereinafter described. Again, as was described with reference to the contact members 89a, 89b and 89c, the lower or duplicate set of contact members are held in place within the recesses by a lower insulation disc 88 set within and frictionally or otherwise secured within the open end of the shell 82. As shown in Fig. 11, projecting terminal ends 90 and 91 of the contact members are accessible through suitable slots 94 and 95 in the shell 82 so that ready connection of conductors may be made therewith.

In order that the circuit of the device may remain open while drilling is in progress and be closed upon interruption of the drilling operation to initiate the signalling current we employ the "agitation" switch shown in Figs. 9 and 10.

The selected form of agitation switch or vibration responsive switch disclosed herein comprises an elongated, tubular body member, preferably having an external diameter approximately equal to the external diameter of the angle measuring devices 16, the relays 23 and sounding device 22, so that it will fit readily within the housing 15. Extending from the upper end of the body 96 is a longitudinal bore 97. The body member 96 is preferably made of steel, or other suitable metal, and in order to provide the necessary insulation for electrical contacts, as herein-after described, we prefer to line the bore 97 with a tubular section of insulation material 98. The lined bore 97 defines a vertical cylinder in which is mounted a ball float 99, preferably constructed of steel or similar metal.

Located at the lower end of the bore 97 are a pair of electrical terminals, or contact members 100 and 101, which may comprise enlarged heads on slender bolts 102 extending from the bore 97 to the lower end of the body member 96, suitable insulation as indicated at 103 being interposed between the contact members 100 and 101 and the metal of the body member, while the bottom of the bore 97 may be formed by a disc or insulation material 104 having a centrally disposed opening 105 therein.

The bore 97 may be disposed eccentrically in the body 96 to permit the second bore or by-pass bore 106 to be disposed within the body member. The by-pass bore 106 has a lateral portion 107 thereof, extending laterally of the body member to intersect the longitudinal axis of the bore 97. Extending from the lateral portion 107 of the by-pass bore and into communication with the main bore 97 is a valve passage 108 which includes a seat 109 for a ball check valve 110. The upper end of the main bore 97 and the upper end of the by-pass bore 106 terminate somewhat short of a plug or cap 111, employed to seal the upper end of body 96.

Thus, by filling the bore 97 and the by-pass bore 106 with oil or similar relatively heavy fluid, any shaking or agitation or vibration of the body member 96 will cause an upward and downward movement of the ball 99. The upward movement of the ball 99 will tend to draw a portion of the liquid into the bore 97 below the ball 99, while such liquid which has been so drawn into the bore 97 will be prevented from escaping from below the ball 99 by a check valve 110.

Thus, during all vibration or agitation of the body 96 and the ball 99 and the check valve 110 will act as a small mechanical liquid pump tending to lift the ball 99 upwardly within the bore 97 and to hold the ball 99 separated from the con-

tact members 100 and 101. The diameter selected for the ball 99 relative to the diameter of the free open space within the bore 97 is such that a small leakage of the liquid is permitted past the ball 99 so that in the event the body 96 is held at the position of rest for an appreciable length of time, sufficient quantity of the liquid below the ball 99 will leak past and permit the ball 99 to descend into electrical contact engagement with the contacts 100 and 101. While, by proper selection of the diameter of the ball and the bore 97 will accomplish this result within relatively narrow limits, we prefer to provide an adjustable leakage control by which the time required for the ball to descend into engagement with the contacts 100 and 101 may be carefully regulated. Such adjustment device is readily comprised of a small leakage bore 112 intersecting both the main bore 97 and the by-pass bore 106, a suitable set-screw or needle-valve 113 being threaded into the leakage bore 112 by which the effective area of the bore for leakage of fluid from the lower end of the bore 97 may be carefully and accurately regulated. As will be obvious, the foregoing construction is extremely rugged and capable of withstanding considerable shocks and abuse and is particularly capable of withstanding any violent vibrations or agitations which might be produced at the drilling tool during its normal drilling operations.

While one such agitation responsive switch 24 is employed to start the measuring and transmission operations, a second such switch 24a may be employed for disconnecting the instrument should the drilling operations be interrupted or paused for longer than the length of time necessary to make the angle measurement and to transmit them to the ground surface. We prefer, for the purpose of insuring that the indications will be received and properly translated at the ground surface to permit the sequencing relays 23 and the angle measuring devices to operate through more than one complete cycle necessary to bring into action all of the angle measuring devices 16 so that whenever the drilling operations are interrupted or paused a repetition of the angle measurements will be made at the ground surface at least two times and preferably three or four times, and then the switch 24a will operate to open the circuits as will fully appear hereinafter to conserve the life of the batteries or other source of electric supply, preventing undue depletion thereof during prolonged cessation of the drilling operations.

The switch 24a may be identical in its construction to the switch 24, hereinbefore described with reference to Figs. 9 and 10, the only difference required between these switches is a suitable adjustment of the adjusting screw 113 to prolong the time period between the cessation of vibration or agitation of the switch and the final closing of its contacts 100, 101 by the ball 99.

We have illustrated in Fig. 8 a novel electric circuit arrangement which is particularly adapted for use with the various switches, relays and angle measuring devices hereinbefore described. This system is simple and straightforward and operates to insure that a monitor signal will be produced at the ground surface to determine whether or not the instrumentalities are in operative condition at the time the measurement is desired, irrespective of the angular inclination of the well bore.

The circuit also provides for connecting each

of the angle measuring devices in sequence to the signalling device so that the signalling device will be actuated a number of times corresponding to the number of angle measuring devices having their contacts closed by displacement of the rolling ball from its normal or central position.

The source of electric current which is illustrated in Fig. 8 as being employed to energize the various electrical circuits preferably comprises the battery 25. The wires from the battery and the wires comprising the interconnecting circuits between the various relays, switches and the like may be run through suitable wiring channels or conduits provided within the housing 15.

Reference to Fig. 5 will indicate that the interior housing 32 which is employed to enclose the coil 33 of the signalling device may be readily extended down throughout substantially the entire length of the instrument housing 15 and may be provided with suitable slots or openings therein through which the various electrical conductors may be passed to permit their connection to the various switches and relays assembled within the inner housing 32. The inner housing 32 is preferably spaced somewhat inwardly of the interior of the housing 15 to provide an annular space in which the various electrical conductors may be run. If desired, however, a relatively long slot may be provided in the inner housing 32 for the accommodation of wiring and in such event the inner housing 32 may have a diameter sufficient to snugly fit the interior of the main housing 15.

In Fig. 8 the conventional electrical symbols have been employed. It will be noted therein that a part of the relays are indicated by the conventional symbol for an instantaneous relay, whereas, the remainder of the relays are indicated by the conventional symbol employed for indicating a "retarded" relay. The instantaneous relays represented on Fig. 8 comprise relays 23 which are not provided with the copper collar 81 previously described as comprising a time delay device, whereas, those indicated as "retarded" relays comprise relays 23 equipped with the shading coil or copper collar 81.

In the circuit illustrated in Fig. 8 we have selected for each of the angle measuring devices to be employed in any one instrument desired a pair of relays. In the diagram we have illustrated the circuit arrangement for four angle measuring devices 16. We have numbered the selected angle measuring devices as A, B, C and D to be connected to the signalling device in sequence in the order named. The relays associated with the angle measuring device A are designated by the reference characters A1 and A2, whereas, those associated with the angle measuring devices B, C and D are likewise designated by the reference characters B1, B2; C1, C2; and D1, D2. The previously referred to monitor signal is produced at the beginning of each cycle of angle measuring operations by monitor relays designated by the reference characters M1 and M2.

A more ready understanding of circuit connections and the operation of the various relays and devices illustrated herein may be had with reference to an assumed set of operative conditions. Assuming that the instrument has been located as hereinbefore described upon a drill string which is then drilling a portion of a well bore at some distance below the ground surface, a short pause in the actual rotation of the drill string and drill bit will permit the vibration re-

sponsive switch 24 to close while, as hereinbefore described, the vibration responsive switch 24a will at this time have its contacts open. Closing of the contacts 100 and 101 of the vibration responsive switch 24 will partially complete a circuit extending from the battery or source of current 25 through conductor 115, through contact members 100, 101 of vibration responsive switch 24, thence by way of conductor 116 and the normally closed contacts LX of the line relay L and thence by way of conductor 118 to ground at 119. Thus current will be supplied to ground. The ground indicated at 119 may be extended throughout the remainder of the circuit as a conductor, if desired, but in order to facilitate manufacture and assembling of the various devices in the housing 15, we prefer that conductor 118 be grounded to some metallic part of the housing 15 as indicated at 119 and that the other portions of the circuit which are to be connected to the conductor 118 be also connected to the metallic parts of the housing, such other connections being also indicated in Fig. 8 by the conventional ground symbol and identified by reference character 119. The grounding of conductor 116 by the closing of the agitation switch 24 establishes a circuit extending from ground by way of conductor 120 through normally closed contacts HX on a circuit-holding relay H, and thence by way of conductor 121 through the coil of a sequence-starting relay S and conductor 122 through conductor 114 and thence back to the battery or source of current 25.

The sequence-starting relay S when energized completes a sequence-starting circuit which extends from ground through conductor 123, the normally open contacts Sa of relay S, thence by way of conductors 124 and 126, the coil of monitor relay M1, conductor 127, normally closed contacts B1x on relay B1 (associated with angle measuring device B) thence by way of conductors 128 and 114 to the battery 25. Relay M1 will therefore be energized and will start to close its contacts M1a and M1b and which, by reason of the time delay interposed by the copper collar thereon will close after the lapse of such time delay period.

The closing of contacts M1b will complete a circuit for the energization of the coil relay M2 which extends from ground, either through conductors 123, 124 and 125 to the contacts M1b of relay M1 or, in view of the fact that at the same time the contacts M1b are closed, the contacts M1a will also be closed and hence provides an auxiliary circuit which extends from ground by way of conductors 129, contact M1a of relay M1, conductor 130, the contacts M1b of relay M1, conductor 132, conductor 133, the coil of relay M2, conductor 134, normally closed contacts D2x (which at this time will be closed) conductor 135, contacts A1y (which also at this time will be closed) and conductors 136 and 114 to the battery or source of current 25.

Again it will be noted that the coil M2, when energized will start to close the contacts of this coil, but due to the employment of the copper collar thereon, the contacts of the relay will be slightly delayed in their closing. However, upon the closing of the contacts M2a of relay M2, a circuit will be completed for energizing the signalling or sounding device 22 to produce the monitor signal or indication. This circuit extends from ground through conductor 137 and contacts M2a, conductor 138 to one terminal of the coil of signalling device 22, from the oppo-

site terminal of which the circuit extends by way of conductor 114 to the battery 25.

It will also be noted that upon the closing of contacts M1a and M1b a circuit is established to the coil of relay M1 which renders this relay self-holding, such circuit extending, as hereinbefore traced through ground and conductors 129, contacts M1a, and conductors 125 and 126 to the coil of relay M1 and thence back to the line as hereinbefore traced. Thus relay M1 will remain energized and hold its contacts closed until such circuit is opened at contacts B1x, which will be actuated only after relay B1 has been energized in the sequence.

Also, it will be noted that the closing of contacts M1a and M1b will complete a circuit energizing the coil of relay A1, which is the next relay in the sequence. This circuit extends, as hereinbefore described, from ground 119 through conductors 129, 130 and 132 to the conductors 139 and 140, the coil of relay A1, conductor 141, the normally closed contacts C1x (which are closed at this time) and conductors 142 and 114 to the battery 25. Relay A1 will close its contacts A1a and A1b at the expiration of the time delay interposed upon this relay, the contacts A1a completing a circuit for holding relay A1 on the line in the same manner as was described with reference to contacts M1a which held relay M1 on the line while contacts A1b prepares a circuit for the energization of relay A2, the latter circuit extending from ground through the contacts A1a and A1b, conductors 143 and 144, the coil of relay A2, conductor 145, normally closed contacts M2x (which at this time are open by virtue of the energization of relay M2) thence by way of conductor 146, the contacts B1y, which at this time will be closed, thence by way of conductors 147 and 114 to the battery.

It will be understood from the foregoing description that while relays M1 and M2 have been energized to produce a monitor signal, the second operation of the signalling device 22 is prevented by reason of the fact that it cannot operate until after relay M2 has been deenergized. Thus, a sufficiently long period of time is provided to insure the production of the monitor beat before any other subsequent signal can be produced.

When relay A1 was energized, and at the expiration of the time delay interposed thereon, closed its contacts A1a and A1b, its normally closed contacts A1y were opened de-energizing relay M2. The de-energization of relay M2 opens its previously closed contacts M2a de-energizing the signalling device 22 while at the same time the normally closed contacts M2x of relay M2 will close completing the circuit for energizing relay A2 as previously described. It will be noted at this point that upon the completion of the circuit to relay A2, it, by virtue of the time delay interposed thereon, will not close its contacts for an appreciable length of time after relay M2 has been, and after it has thereby de-energized, the signalling device 22. However, at the end of this lapse of time imposed upon relay A2 its contact A2a will close, supplying current to the contact ring 21 of the angle measuring device A.

Thus, if at this time the well bore is deviating from the vertical by an angle in excess of that for which the angle-measuring device A is selected, its ball 19 will lie in contact with the contacting ring 21 thereof. Thus, the signalling device 22 will be energized for a second time by way of the circuit which extends from ground through conductor 148 to the base 17 of the angle-

measuring device A (while for convenience in tracing the circuit the connection of the base 17 to ground 118 is shown as extending as a conductor, it will be apparent from an inspection of Fig. 2 that the base 17 is grounded directly to the case or housing 15). The circuit then extends by way of the ball contact 19, contact ring 21 of angle-measuring device A, thence through conductor 149, the contacts A2a to conductor 138 and thence to the signalling device 22 back to the battery, as previously described for the signalling device 22.

It will also be observed that the closing of the contacts A1a and A1b also prepares and completes a circuit to the next relay in the sequence B1 by way of the circuit previously traced for relay A2 to conductor 143, thence by way of conductor 150 and conductor 151 to the coil of relay B1, and thence by way of conductor 152, normally closed contacts D1x (which are closed at this time), thence by way of conductor 153 and conductor 114 to the battery.

Relay B1 will thereafter close its contacts B1a and B1b as shown when the time has elapsed which has been imposed upon this relay as its time delay, the contacts B1a completing a holding circuit for the relay B1 in the same manner as was described with reference to the holding circuit for relays M1 and A1.

It will be noted that relay M1 has up to this time maintained its energized condition, but immediately upon the actuation of relay B1 this relay will open its normally closed contacts B1x (in the circuit for relay M1) and the relay M1 will at this time be de-energized. Relay B1 when energized will also open its contacts B1y which will de-energize relay A2. However, relay A2, will, by reason of the time delay interposed upon it, open its contacts slowly, opening the previously energized sounding device circuit through angle-measuring device A after the elapse of a predetermined length of time, and thus de-energizing the signalling device 22, preparing it for a subsequent energization, provided, the angle-measuring devices further along in the sequence have been so tilted by angularity of the well bore as to hold their balls or contact members into circuit closing position.

Relay B1 having closed its contacts B1a and B1b prepares a circuit for energizing relay B2, which circuit extends from ground through contacts B1a, conductor 154, the contacts B1b, conductors 155 and 156 to the coil of relay B2, whence the circuit extends through the normally closed contacts A2x of relay A2 (which at this time are in open circuit condition), thence through normally closed contacts C1y of relay C1 (which at this time will be closed) and thence by way of conductor 114 to battery 25. However, at this point, it will be noted that at approximately the same time that the relay contacts B1b are closed, the relay contacts B1y have de-energized relay A2 so that upon the lapse of the predetermined length of time imposed upon relay A2 the contacts A2x will close and relay B2 will be energized. Relay B2 when energized will after a time delay close its contacts B2a, preparing the circuit for angle-measuring device B which will be immediately completed provided the ball contact for angle-measuring device B has been shifted to its abnormal position by reason of the deviation of the well bore from vertical.

Assuming that the well bore has deviated from the vertical only by such angle as will actuate

angle measuring device A but will not actuate angle measuring device B, the signalling device 22 will not be operated in response to energization of relay B2, hence the result of the operations thus far described will be that the signalling device 22 will have been actuated twice and will have produced two spaced groups of vibrations which will be received at the ground surface as two spaced sets of vibrations or signals followed by a pause of greater length of time than the normal pause between adjacent beats or signals. To continue the operation, however, of the sequence relays which will continue to sequentially connect angle measuring devices C and D in circuit with the signalling device 22, relay B1, when it has been energized, will complete a circuit for relay B3. Relay B3 is employed solely for the purpose of removing the starting relay S from the line, so that thereafter the sequence of connection of the angle measuring devices B, C and D and the production of the monitor signal will be continuously repeated in a repeated series of time cycles. The circuit for relays B3 extends through conductor 155 in the same manner as was described with reference to the relay B2, the relay B3 having its coil connected between conductors 155 and 114 in shunt circuit relation to the relay B2.

Relay B3, when energized, will instantly close its contacts B3a which are in circuit with the sequence holding relay H. Thus, sequence holding relay H will be energized through contacts B3a of relay B3, conductor 158, conductor 159, coil of relay H and conductors 160 and 114 to the battery 25. Relay H, when energized, closes the self holding contacts Ha which completes a self-holding circuit for this relay by way of conductors 120 and 159.

The energization of sequence holding relay H opens its normally closed contacts Hx, which as hereinbefore described, are in circuit with the starting relay S, thereby de-energizing starting relay S and causing it to open its normally opened contacts Sa and permitting it to close its normally closed contacts Sx.

The normally closed contacts SX are interposed in a conductor 163, which inter-connects the relays associated with the last angle measuring device in the system with the energizing circuits for the first set of relays in the sequence, namely, the monitor relays M1 and M2, so that once the sequence of relays has been started by the sequence-starting relay S and the sequence has been carried through one complete set of operations for connecting the entire set of angle measuring devices successively and consecutively with the signalling device 22, the sequence will be repeated continuously until the main energizing circuits are opened by the second of the agitation responsive switches 24a, which, as will be recalled, will close its contacts at a relatively long predetermined time after the drill string has been brought to rest either for the purpose of making the angle measurement or for any other purpose.

Continuing the operation, the description of the diagrammatic arrangement shown in Fig. 8 the next relay in the sequence is relay C1 associated with angle measuring device C. The relay C1 will be energized as soon as the contacts B1b on relay B1 have closed, the circuits for the relay C1, extending by way of ground through contacts B1a and B1b of relay B1 and thence by way of conductors 155 and 164, the coil of relay C1, conduc-

tor 165, normally closed contacts M1x (which will now be closed since relay M1 is de-energized) and conductors 166 and 114 to the battery 25. Relay C1, when energized, closes its contacts C1a and C1b after the lapse of whatever time delay is interposed upon relay C1, the contacts C1a closing a self-holding circuit for the relay C1 in the same manner as hereinbefore described for relays M1, A1 and B1, while the contacts C1b will prepare a circuit for the energization of relay C2, associated also with the angle measuring device C, which circuit, however, will not be closed until after de-energization of the relay B2 which had connected the angle measuring device B with the signalling device 22. Upon the de-energization of relay B2, however, the circuit for relay C2 will be completed, this circuit extending through the contacts C1b of relay C1, as hereinbefore described, and thence by way of conductor 167, the coil of relay C2 and thence through normally closed contacts B2x of relay B2, normally closed contacts D1y of relay D1, and thence by way of conductor 114 to the battery 25.

Relay C1, when energized, will open its contacts C1y de-energizing relay B2 which will after the lapse of the time delay imposed upon relay B2 open its contacts B2a disconnecting the signalling device 22 from possible energization by angle measuring device B. At the same time relay C2 will be energized and upon the lapse of the predetermined time imposed upon relay C2, this relay will close its contacts C2a, coupling angle measuring device C with the signalling device 22 so that should the ball contact of this angle measuring device C be in circuit closed position the signalling device 22 will be actuated for a fourth time in the sequence. However, we have assumed that the angle of deviation at the time of making the measurement was not sufficient to place the ball contact of angle measuring device C in circuit closing position and hence no further signal will be given by signalling device 22.

Relay C1 when it was energized and closed its contacts C1a and C1b, also completed the circuit for energizing relay D1, which circuit extends through the contacts C1a and C1b as hereinbefore traced, and thence by way of conductors 168 and 169, through the coil of relay D1 and thence by way of conductor 170, normally closed contacts A1x of relay A1 and thence back to the battery 25 by way of conductor 114.

Relay D1, which is associated with the last of the angle measuring devices D, operates in the same manner as was described with reference to relays M1, A1, B1 and C1, and after the lapse of the time imposed upon this relay will close its contacts D1a and D1b and at the same time open its contact D1y de-energizing relay C2 and D1x de-energizes B1 in the same manner as the preceding relay in the sequence. The contacts D1a will complete the self-holding circuit for the relay D1 while the contacts D1b will prepare a circuit for energization of relay D2, which is also associated with the angle measuring device D. The circuit for relay D2 extends through the contacts D1a and D1b, and thence by way of conductor 171 through the coil of relay D2 and thence through normally closed contacts C2x of relay C2 and normally closed contacts M1y of relay M1, and thence to the battery 25 by way of conductor 114.

As hereinbefore stated, energization of relay D1 opens its normally closed contact D1y, de-energizing relay C2, so that upon the lapse of

the time imposed upon relay C2 this relay will open its contacts C2a disconnecting the signalling device 22 from possible operation by the angle measuring device C and at the same time completing the energizing circuit for the relay D2.

Now upon the lapse of the time imposed upon relay D2 this relay will close its contact D2a and connect the signalling device 22 in circuit with the angle measuring device D, so that should this angle measuring device have its ball contact in circuit closed position the signalling device will be operated for the fifth time in the cycle. However, as stated before, we have assumed that the angle of deviation is such that only angle measuring device A will be in circuit closed position, and hence, even though each of the angle measuring devices is consecutively connected with the signalling device, the signalling device will be operated only twice in each completed cycle, namely, once by the monitor relay and once by angle measuring device A.

At this point it might be well to review the effect of the foregoing operations upon the signal receiving and recording apparatus. As stated, during the complete time cycle required for the sequential energization of all of the relays M1 to D2, the signalling receiving apparatus or the recording device will be operated twice at the beginning of the cycle and thereafter will not be operated during the remainder of the cycle.

As will be apparent to those skilled in this art, it is possible that either through inattention or some other reason the driller or person who should receive the information at the ground surface may have failed to observe the complete set of signals transmitted thereto, and hence we prefer to so arrange our device and our system that the same set of measurements, the same set of signals will be produced at least a second time, that is a second cycle of operations will be performed repeating the information obtained and transmitted during the initial operation hereinbefore set forth. The manner in which we have accomplished this repetition of the operations lies in inter-connecting the relay D1 with the monitor relay M1, that is we interconnect the relay for the last of the angle measuring devices with the monitor relay so that after the last angle measuring device has been connected in the circuit it will start the entire sequence all over again by starting the operation of the monitor relay M1.

Referring to Fig. 8 it will be observed that when relay D1 closed its contacts D1a and D1b, it completed the circuit for the energization of relay M1 which is independent of the initial circuit required for the energization of relay M1. This circuit extends by way of the contacts D1a and D1b on relay D1 and thence by way of conductor 163 through normally closed contact Sx of the sequence starting relay S (which at this time it will be recalled is de-energized) and thence the circuit continues by way of conductors 172, 124 and 126 to the coil of relay M1 and thence back to the battery 25 as previously traced for the relay M1. Relay M1, when re-energized will close its contacts M1a, M1b energizing relay M2 in the same manner as was previously described for the energization of relay M2. Relay M2 will again operate its contacts M2a producing the monitor signal and the entire sequence of operations of relays A1, A2, B1, B2, C1, C2, D1, and D2 will be repeated as long as current from battery 25 is supplied to the relays.

However, since it is probably unnecessary to

repeat the cycle of operations for more than say three or four times, we conserve the energy of the battery 25 by disconnecting the relays as a result of the operation of the second agitation switch 24a. When agitation switch 24a closes its contacts the circuit will be completed for a line disconnecting relay L, which circuit extends from the battery or source of current 25 through conductor 115, the contacts of agitation switch

- 5 switch 24a. When agitation switch 24a closes its contacts the circuit will be completed for a line disconnecting relay L, which circuit extends from the battery or source of current 25 through conductor 115, the contacts of agitation switch 10 24, conductor 116 and thence by way of conductor 173, the contacts of agitation responsive switch 24a, conductor 174, the coil of line disconnecting relay L and conductors 175 and 114 to battery 25. The line disconnecting relay L when 15 energized will open its contacts Lx and open the circuit between the battery 25 and ground and all of the relays contained within the circuit beyond contact Lx will be disconnected and will remain disconnected until the drill string is again operated and a further set of measurement is desired.

An inspection of the wiring arrangement shown in Fig. 8 will demonstrate that the circuit employed within is an extremely simple circuit to 20 connect up and that it is peculiarly adapted, by reason of the connections of the contacts of the several relays, to employ the particular character of relay hereinbefore described.

- It will be apparent, therefore, that we have 30 provided an extremely simple device which may be permanently located on the drill string and hence is instantly available to the driller for making angle measurements repeatedly throughout the drilling operation, and which does not 35 require the disconnection of any portion of the drill string for the purpose of making the test.

We have also provided a system of sound transmission or signal transmission from an instrument which may be located at any distance below 40 the ground surface, in which we utilize the efficient transmission qualities of the column of liquid which is always present in and during the drilling operations, and we are thereby enabled to avoid any conductors or any other transmission 45 devices extending from the ground surface to the bottom of the hole.

We have also provided an instrument which has each of its elements so designed as to be extremely rugged, almost impossible to break, injure or destroy, particularly the various switches and relays which are employed. The agitation responsive switch, for example, is made of only two moving parts, namely, the relatively heavy rugged ball float and the simple ball-check valve 55 which, as is well known, can withstand the abuses to which it may be subjected during the drilling operations.

The same principle of relatively few moving parts and each of those parts being made in the 60 form of metal ball is likewise employed in the construction of each of the sequence relays so that there are no delicate instrumentalities requiring careful adjustment or careful handling or even careful machining and manufacture.

- 65 We have also shown a simple but effective means for producing signals of predetermined frequency and means for receiving such signals, which in themselves act as a filter to filter out and prevent interference between the signals desired to be transmitted and other extraneous noises which may be present either at the bottom of the hole or at the ground surface.

Also we have described an extremely simple and effective manner in which the instrument 70 may be mounted within the drill string, so as to

utilize the greatest possible effect of transmission of the signals to the mud stream or fluid column and yet avoid any appreciable injury to the device or to its mounting apparatus by reason of the fact that such circulating mud fluids are usually highly abrasive. Further, it will be recalled that the mounting of the device within the drill string is located out of the path of core bits, or other instrumentalities which may be employed during the drilling of the well to pass down through the circulation openings or passages.

While we have shown and described the preferred embodiment of our invention, we do not desire to be limited to any of the details hereinbefore illustrated and described, except as defined in the appended claims.

We claim:

1. In a system for measuring conditions existing in a well bore having extending thereto from above the ground surface a tubular rotary drill string which contains a column of liquid extending to a point above the ground surface, said drill string including also a stationary portion disposed above the ground surface, a device secured to the lower end of said drill string for measuring a condition in said well bore and including a signal producing means including a diaphragm means exposed to said column of liquid at the location of said device, means for vibrating the diaphragm at a predetermined frequency upon actuation of said signalling device for creating a series of pressure waves in said liquid column, means above the ground surface secured to said stationary portion of said drill string and exposed to the effect of the pressure waves created by said signal producing means for receiving said waves, and means for rendering said signal receiving means responsive only to pressure waves of predetermined frequency.

2. In combination with a device insertable into a well bore containing a liquid column extending to the ground surface, a signal producing means associated with said device and including a diaphragm located on said measuring device and exposed to the liquid column at the location of said device within said bore, said signal producing means including a weight suspended from said diaphragm by means of a resilient rod, the mass of said weight and the dimensions of said rod being selected to vibrate said diaphragm at a predetermined frequency, and signal receiving means at the ground surface tuned to receive signals or vibrations only of said predetermined frequency.

3. In a system for measuring conditions existing in a well bore which contains a drill string and a column of liquid circulating therethrough, a device for measuring a condition existing in said well bore, means mounting said device in said drill string adjacent the lower end of said string and including a tubular mounting member having an interior bore extending therethrough with a cross-sectional area in excess of the cross sectional area of the normal fluid opening through said drill string, whereby the velocity of the fluid through said mounting member is less than the velocity thereof through other parts of said string, and the abrasive action of said fluid on said measuring device is thereby minimized, and means for securing said measuring device in said mounting member off-set from the longitudinal axis of said drill string to per-

mit the passage of tools through said drill string and through said mounting member.

4. In a system for measuring conditions existing in a well bore which contains a drill string and a column of liquid circulating therethrough, a device for measuring a condition existing in said well bore, means mounting said device in said drill string adjacent the lower end of said string and including a tubular mounting member having an interior bore extending therethrough with a cross-sectional area in excess of the cross sectional area of the normal fluid opening through said drill string, whereby the velocity of the fluid through said mounting member is less than the velocity thereof through other parts of said string, and the abrasive action of said fluid on said measuring device is thereby minimized, and means for securing said measuring device in off-set relation relative to the longitudinal axis of said drill string and counterweight means on said drill string to compensate for the unbalancing of the drill string by said measuring device.

5. In a system for measuring conditions existing in a well bore which contains a drill string and a column of liquid circulating therethrough, a device for measuring a condition existing in said well bore, means mounting said device in said drill string adjacent the lower end of said string and including a tubular mounting member having an interior bore extending therethrough with a cross-sectional area in excess of the cross sectional area of the normal fluid opening through said drill string, whereby the velocity of the fluid through said mounting member is less than the velocity thereof through other parts of said string, and the abrasive action of said fluid on said measuring device is thereby minimized, and means for securing said measuring device in off-set relation to the longitudinal axis of said drill string, said measuring device including a plurality of batteries and counter-balancing means disposed in diametrically opposed offset relation with respect to the longitudinal axis of said drill string, said counter-balancing means including storage means for a supply of battery cells for the operation of said measuring device.

6. In a system for measuring conditions existing in a well bore which contains a conduit through which liquid is pumped into said well bore, said conduit having therein a column of liquid extending to a point above the ground surface, the combination of a signal producing device located in the well at some distance below the ground surface for producing pressure wave impulses in said column of liquid, a receiving device secured to said conduit above the ground surface for receiving said pressure wave impulses including a diaphragm exposed to the liquid in said conduit, and means rendering said diaphragm responsive particularly to pressure wave impulses of predetermined frequency.

7. In a system for measuring conditions existing in a well bore, a device insertable in said well bore for measuring conditions existing therein, means for repeatedly transmitting said measurements from said device to be received and translated at the ground surface, said transmitting means including an electric circuit and a source of electric current located on said measuring device, means for conserving the life of said source of electric current including means for opening said electric circuit whenever said device is moved

in the well bore and for completing said circuit only when said device is brought to a condition of rest, and additional means for opening said circuit a predetermined time after said device has been brought to rest and subsequent to the completion of the circuit by said first named means.

8. In a system for measuring conditions existing in a well bore, a device insertable in said well bore for measuring conditions existing therein including electric switch means closable in response to the existence of a condition to be measured, means for transmitting said measurements from said device to be received and translated at the ground surface, said transmitting means including a source of electric current located on said measuring device connected in an electric circuit with said switch means, means for conserving the life of said source of electric current including means for opening said electric circuit whenever said device is moved in the well bore and for completing said circuit only when said device is brought to a condition of rest, and additional means independent of said switch means for opening said circuit a predetermined time after said device has been brought to rest and subsequent to the completion of the circuit by said first named means.

9. In a system for measuring conditions existing in a well bore, a device insertable in said well bore for measuring conditions existing therein, signaling means on said device operative to repeatedly transmit to the ground surface signals corresponding to the condition measured by said device, means for rendering said device operative to effectively measure said condition only when said device has been brought to rest in said well bore, and means for rendering said device inoperative to measure said condition after the lapse of a predetermined length of time after said device has been brought to rest.

10. In a system for measuring conditions existing in a well bore, a device insertable in said well bore including an electric switch means closable in response to the existence of a condition to be measured; an electrical signal producing means connected in a main partial circuit with a source of electric energy; a plurality of time delay relays connected in a chain circuit with each other and with said source, said chain circuit being so arranged that said relays are alternately energized and de-energized in a timed succession; and a pair

5 of branch circuits for completing said main partial circuit, one of said branch circuits including contacts of one of said time delay relays and the other of said branch circuits including in series contacts of another of said time delay relays and said electric switch means.

11. In a system for measuring the inclination of a well bore, a device insertable in said well bore including a plurality of electric switch means each closable by inclination of said device from the vertical by a different amount; a source of electric energy; a plurality of time delay relays connected in a chain circuit with each other and with said source, said chain circuit being so arranged that said relays are alternately energized and de-energized in a timed succession; an electrical signal producing means connected in a main partial circuit with said source; and a plurality of branch circuits connected to complete said main partial circuit, each of said branch circuits including in series a different one of said electrical switch means and a contact of a different one of said time delay relays.

12. In a system for measuring the inclination of a well bore, a device insertable in said well bore including a plurality of electric switch means each closable by inclination of said device from the vertical by a different amount; a source of electric energy; a plurality of time delay relays connected in a chain circuit with each other and with said source, said chain circuit being so arranged that said relays are alternately energized and de-energized in a timed succession; a starting switch closable to energize the first of said relays in said chain circuit, the last relay in said chain circuit being connected to re-energize said first relay; an electrical signal producing means connected in a main partial circuit with said source; a plurality of branch circuits connected to complete said main partial circuit, each of said branch circuits including in series a different one of said electrical switch means and a contact of a different one of said time delay relays; and cut off means for disconnecting said source a predetermined time after closing of said starting switch.
